UNITED STATES PATENT OFFICE.

WIRT J. WILLS, OF MEMPHIS, TENNESSEE.

PUMPING SYSTEM.

1,175,856.

Specification of Letters Patent. Patented Mar. 14, 1916.

Application filed May 23, 1910. Serial No. 563,032.

To all whom it may concern:

Be it known that I, WIRT J. WILLS, a citizen of the United States, residing at Memphis, in the county of Shelby and State of Tennessee, have invented certain new and useful Improvements in Pumping Systems, of which the following is a specification.

My invention relates to a water-supplying system and its objects are to provide a system that will obviate the necessity for a central pumping station, or reservoirs, in supplying water under pressure to the mains from separated wells, will avoid the expense required for plants to effect two or more separate pumpings, will enable large trunk mains to be dispensed with, with the consequent saving of expense of construction and reduction of friction, will enable the pressure to be increased at any particular point where most needed and will enable the utilization of segregated units of source, such as wells, without interference in the flow from the respective wells.

To these ends, my invention consists, generally stated, in a system comprising pumping means for lifting the water from the well and forcing it under pressure from the point to which it is raised directly to distributing means such as mains, tanks, or reservoirs, in a continuous flow and by a single operation from suitable motor means.

This invention is embodied in the combination of the elements of a water-lifting well pump, with force pump elements in direct communication with the well-pump elements and exerting pressure on the water to force it out to distributing means under pressure, such receiving and distributing means being in direct communication with the forcing-pump elements and common motor means for driving both the well pump elements and the force pump elements. The lifting pump and the forcing and pressure imparting pump may be embodied in a single pump-structure or in two separate devices.

In water works systems where wells are used as a source of supply, great difficulty is experienced on account of the flow of one well interfering with that of another. Consequently a system of pumping which will permit of the segregation of the wells is essential to the successful utilization of a plurality of such units of supply. In all the systems of pumping so far devised, even although a number of wells have been placed

in different localities, still they must be in comparatively close proximity, so as to be pumped from a central pumping station. Segregation of the wells would obviate the use of large trunk lines of mains, would increase the pressure at the point where it was most needed and would necessarily reduce the friction of the water in the pipes to a minimum. Up to the present time, so far as I am aware, no system has been proposed which would admit of utility in accomplishing this end. My system permits of the wells being bored as far apart as is desired so as not to interfere at all, the water put into the mains under the required pressure and the expense of building large plants done away with, inasmuch as the power may be electric, gas engine, gasoline or otherwise and the whole pumping outfit may be placed under a street, side-walk, or lot, obviating the necessity of building house or plant.

In the experiment I have made, a 10" well was bored under the street and a chamber dug out about 10' x 18'. Into this was placed the pumping outfit. As the pumping means are run by an electric motor, only a wire goes into the chamber. A concrete cover is put over the street and no obstruction is offered by the mechanism and a surface structure for housing obviated. Another advantage in this form of pumping is that it does not require constant attention, one man being able to look after from a half dozen to a dozen pumps, inasmuch as his duties are principally watching the lubrication. With my invention water is pumped from wells of any depth into mains under the required pressure, without the use of pumping stations, or reservoirs employed for the purpose of obtaining a required head of water. From the fact that pumping stations do not have to be built, large mains are made unnecessary and, the attendance upon the pumping being so slight and the water only having to be pumped once, the price of the water put into the main is reduced to a minimum, which is very essential where water is sold.

The preferred forms of embodiment of my invention are illustrated in the accompanying drawings in which—

Figure 1 is a side view in elevation, partly broken away, of the pumping system, and showing a motor, a well pump and a rotary force pump combined; Fig. 2, a modified form of the invention in which a centrifugal

force pump is employed in connection with the well pump and motor; Fig. 3, a side view in elevation of a series of sources and pumping units, adapted for a system when a plurality of properly segregated wells is required for the demands of separate localities; Fig. 4, a detail transverse section looking toward the left of Fig. 1, of the pressure force pump shown in said view and 10 also showing the main driving shaft and gear connection with the pump, and Fig. 5, a detail vertical section of the centrifugal pressure force-pump shown in Fig. 2.

Referring to the drawings, 1 designates 15 a well casing into which extends an ordinary lift or impeller pump, the form shown, consisting of a screw pump 2, which is driven by bevel gears 3 and 4. The gear 4 is carried by a shaft 5 mounted in suitable 20 bearings 6 which are supported on a suitable masonry foundation 7. On this foundation is also mounted a force pump 8, which may be of any desired type adapted 25 for forcing the water therefrom under pressure and is shown as of the ordinary force pump class. A connecting pipe 9 leads from the top of the well to the force pump providing a direct and continuous communication between said parts. A delivery main 30 10 communicates directly with the force pump receiving the water under pressure therefrom and leads to any suitable branch pipes, reservoir or other distributing means.

A motor device 11, common to both 35 pumps, consisting preferably of an electric motor although a gasolene or steam engine may be employed, is mounted on the foundation, preferably between the two pumps. The shaft 12 of this motor at one end has 40 a gear 13 meshing with and driving a speed-reducing gear 14 on the shaft 15 of the force pump and at the other end has a connection 16, consisting preferably of a flexible coupling engaging the shaft 5 of the 45 lift pump 2. By this arrangement the two pumps are synchronously driven by the same operation so that the supply of water pumped from the well and forced from the force pump may accord and the flow from 50 well to force pump be continuous and so that water not under pressure will be delivered from the lift-pump to the force-pump and pressure imparted thereto by the latter and the water pumped therefrom into 55 the mains under pressure sufficient for service delivery at the required head.

A regulating waste pipe 17 having a closed upper end rises from the connecting pipe 9, the function of which is upon any 60 stoppage of the force pump, to automatically stop the feed of the well pump by the pressure of an accumulated column of water therein on the water in the well. The delivery pipe is provided with a check valve 65 18 to prevent the back-flow of the water.

In Fig. 2, a form of my invention is illustrated in which a single pump structure 19 comprising a pump of the screw type for lifting the water from the well 20 and a pump of the centrifugal type for forcing it 70 under pressure in a continuous flow by the same operation to the receiving means 21. In this device the motor 22 may be mounted above the centrifugal pump, driving the latter and the lift pump by a direct line shaft 75 connection.

In the utilization of my invention, wells 80 may be sunk at such locations as are suitable and such that the flow of water from the different wells will not interfere. The underground chamber at the well being built, the pumping arrangement is mounted therein and such number of wells may be provided as are required by the needs of different localities. 85

In operation the water is pumped directly from the well into the force pumping element of the system from which it is delivered under pressure in the same continuous operation, directly into the receiving and 90 delivering medium employed to deliver the water to the distributing branches.

Owing to the arrangement and operation 95 above described, my invention makes it possible to dispense with the necessity of pumping to a large central reservoir from which the water is distributed by natural flow or by pumping from a central station and also enables the large trunk lines necessarily employed with the central distributing station 100 system to be dispensed with.

Any desired form of well pump, force pump and motive power device may be employed and my invention does not reside in the particular construction of such mechanisms. 105

Having thus described my invention, what I claim is:—

1. In a water-supplying system, in combination with an original source of supply of 110 water not under pressure, water receiving and distributing means, means for raising and delivering the water from said source to said receiving and distributing means in a continuous flow and under the required 115 service pressure, comprising a local unitary power and pumping device located at the source of supply and consisting of a non-pressure pump capable of raising the water from below the suction lift and which merely 120 lifts the water from said source initially, a separate pressure imparting pump of the same capacity as the first pump and in constant and direct communication with the lifting pump and acting to force the water under 125 the required service pressure to said distributing means, and power means for synchronously driving said pumps, substantially as described.

2. In a water-supplying system, in com- 130

- 5 bination with an original source of supply of water not under pressure, delivery mains, a lifting pump capable of raising the water from below the suction lift and which 5 merely lifts the water from below the suction lift without imparting pressure thereto, a pressure-imparting pump of the same capacity as the lift pump on said upper level and in direct and constant communication 10 with the lifting pump for alone imparting service pressure to said water, motor means for synchronously driving said pumps, and means of direct communication between said pressure imparting pump and 15 delivery mains, whereby the water may be lifted from said source of supply and pumped directly into the mains under the required service pressure, substantially as described.
- 20 3. In a water-supplying system, in combination with an original source of supply of water not under pressure and below the suction lift of pumps, receiving and distributing means, a non-pressure pump 25 adapted and arranged for raising a constant volume of water from below the suction lift point and which merely lifts the water from said source, a separate pressure-imparting force pump in constant action 30 and direct communication with said first pump during operation and adapted to receive the water therefrom and in constant communication with the receiving and distributing means and a common motor for 35 driving both pumps synchronously, substantially as described.
4. A water supply system composed of a plurality of deep wells, separated far enough from each other for the flow of one 40 or more not to interfere with the flow of the others, water mains connected together for distributing the water as desired, rotating non-suction lift pumps, which simply lift the water from the wells to an upper level 45 without imparting pressure thereto, pressure imparting pumps corresponding to said lifting pumps and of the same capacity thereof on an upper level and in direct communication with the respective lift 50 pumps, for alone imparting required pressure to the water forced into the mains, motive power for synchronously driving said pumps and means of direct communication between said pressure imparting 55 pumps and delivery water mains, whereby the water may be lifted from said deep wells and pumped directly into the mains under the required service pressure in a continuous flow from the well to the main.
5. In a water-supplying system, in combination with segregated and non-interfering water supply units, local pumping systems, one for each unit and each comprising a pump which merely lifts the water from the supply below the suction lift and a pressure-imparting force pump of the same capacity of the lift pump, said pumps in direct communication with the supply and with each other, and delivering water from said supply in a continuous flow under pressure, 65 motive power means for each unit for synchronously driving both pumps and receiving and delivering means connected with each unit, substantially as described.
6. In a fluid pumping mechanism, in combination with a rotating non-suction water-lifting impeller pump member, a pressure imparting pump member of the same capacity as the first pump and arranged to receive the discharge from the lifting member 70 and motor means for synchronously driving both pumps, substantially as described.
7. In a fluid pumping mechanism, in combination with a rotating, non-suction water-lifting impeller pump, a pressure imparting 75 pump adapted to receive the water in a continuous flow and force it into suitable receiving means in the same continuous flow under pressure, the said pump members being so proportioned in delivery capacity 80 that the lift pump will supply the fluid at the rate required by the pressure pump, and a common motor for synchronously driving said pump members.
8. In a fluid pumping mechanism, in combination with a screw propeller lifting member, a pressure imparting pumping element of the same capacity as the lifting element and in continuous communication therewith 85 and arranged in position to receive the discharge from the said lifting member and a motor connected with said lifting and pump elements.
9. A fluid pumping mechanism consisting of a screw propeller lifting member capable 90 of raising the water from below the point of suction lift, and a centrifugal pumping element of the same capacity as the lifting member and arranged in position to receive the discharge from the lifting element, and 95 a motor connected with said lifting and pumping elements.
